(57) **CLAIM**

The ornamental design for a trim strip for tablet case, as shown and described.

DESCRIPTION

FIG. 1 is the using state of a trim strip for tablet case showing my new design;

FIG. 2 is the using state thereof;

FIG. 3 is the using state thereof;

FIG. 4 is a first perspective view thereof;

FIG. 5 is a second perspective view thereof;

FIG. 6 is a front view thereof;

FIG. 7 is a back view thereof;

FIG. 8 is a left side view thereof;

FIG. 9 is a right side view thereof;

FIG. 10 is a top view thereof;

FIG. 11 is a bottom view thereof; and,

FIG. 12 is an enlarged view of the selected portion 12 in FIG. 4.

The dash-dash broken lines shown in the drawings depict portions of the trim strip for tablet case that form no part of the claimed design. The dot-dash broken lines in FIGS. 4 and 12 illustrate the periphery of the enlarged views of the trim strip for tablet case and form no part of the claimed design.

1 Claim, 12 Drawing Sheets
